UNITED STATES PATENT OFFICE.

MINOS L. FLETCHER, OF NASHVILLE, TENNESSEE.

DESIGN FOR A GOBLET.

Application filed August 2, 1928. Serial No. 27,669. Term of patent 7 years.

To all whom it may concern:

Be it known that I, MINOS L. FLETCHER, a citizen of the United States, residing at Nashville, in the county of Davidson and State of Tennessee, have invented a new, original, and ornamental Design for Goblet, as shown in the accompanying drawing and described in the following specification, in which—

Fig. 1 is a top plan view, and Fig. 2 a perspective view of the goblet, showing my new design.

I claim:

The ornamental design for goblet as shown.

MINOS L. FLETCHER.
